ARTICLE OF FOOTWEAR

Ernst J. Story, Cincinnati, Ohio

Application April 24, 1942, Serial No. 440,362

8 Claims. (Cl. 36—33)

This invention relates to an article of footwear, and especially to that type of footwear which may be constructed with board-like sole material, rather than flexible sole material such as leather.

An object of the invention is to provide in an article of footwear of the character stated, an improved hinge means between a front section and a rear section of the sole, which is self-cleaning and thereby kept in an operative condition without requiring any special attention on the part of the wearer.

Another object of the invention is to provide an article of footwear having inflexible sole sections joined together with a hinge of which the constituent parts are so related to the sole sections as to prevent binding and stiffening of the joint and resultant discomfort to the wearer.

A further object of the invention is to provide an article of footwear of the class described, which is simple and inexpensive to manufacture, yet highly durable and serviceable as well as comfortable upon the wearer's foot.

These and other objects are attained by the means described herein and disclosed in the accompanying drawing, in which:

Fig. 1 is a perspective view of the article of footwear, showing the front and rear sections separated in the interest of clarity of disclosure.

Fig. 2 is a fragmental side elevational view of the device of Fig. 1, showing the front and rear sections hingedly connected, the view being on a slightly enlarged scale.

Figs. 3 and 4 are fragmental side elevational views showing in detail the hinge means aforesaid.

Fig. 5 is a fragmental side elevational view of a modification.

Fig. 6 is a similar view showing a second modification.

Prior to the present invention, various types of sandals were known to embody front and rear sole sections connected together by means of hinges for the purpose of conformity between the movements of the foot and of the sandal in walking, but in all known prior structures there was encountered the difficulty of excluding dirt, sand and other foreign particles from the hinge connections, so that the hinge connections soon became inoperative due to the compacting of such foreign material between the movable sections. The result of such compacting of foreign material within the joint between the front and rear sole sections, was to eventually so limit the hinging movements as to render the sole

sections practically immovable relative to one another, and as a consequence, the shoe or sandal in a short period of time was little better than one constructed without a hinge connection. As is obvious, a shoe or sandal that will not flex in conformity with the movements of the foot in walking, is uncomfortable and renders walking difficult and awkward.

One of the objects of the present invention is that of providing an article of footwear with relatively inflexible front and rear sole sections joined together with a hinge that is so constructed as to be self-cleaning, that is, the hinge means includes structure operative to clear the hinge of foreign materials and to eject such foreign materials before they may be compacted within the hinge joint. The particular hinge structure disclosed herein is designed to accomplish this objective with the use of means having the advantages of simplicity and low manufacturing costs. A detailed description of the improved article of footwear is given below.

With reference to Figs. 1, 2 and 3 of the accompanying drawing, the characters 12 and 13 indicate, respectively, the rear sole section and the front sole section of the article of footwear. The rear sole section has an upper surface 14 providing a heel supporting area 15 and is shaped similarly to the sole of any conventional shoe. The lower surface 16 of the section may be arched, and may carry a conventional heel 17 of wood, rubber or other acceptable material. Both of the sections 12 and 13 preferably are made of a substantial inflexible board material such as wood, pressed board, or the like. In fact, the use of any suitable material in the sections of the article of footwear need not be limited, so long as the material is substantially inflexible and capable of being shaped or formed to present the necessary elements to be described hereinafter. To aid in a proper understanding of the invention, it may be assumed that the sole sections are of wood, sawed or pressed to impart a proper configuration thereto.

The particular form of means disclosed herein as straps 18 and 19 for holding the article of footwear upon the wearer's foot is of no particular importance to the invention wherefore it is understood that such means may be varied to suit the demands of the dealer or wearer.

In that form of the invention disclosed by Figs. 1, 2 and 3, the rear section 12 includes a forward edge 20 tooled out to form a channel or groove 21 which is of approximate half-cylinder formation, said groove being interrupted at

equal distances from the sides 22 and 23 of the section, by a longitudinal hinge barrel 24 which may be formed integral with the material constituting section 12. The hinge barrel is cylindrical, and is bored longitudinally as indicated at 25. The axis of the bore rests midway between the upper and lower shearing edges 26 and 27 that bound the grooves at opposite ends of the hinge barrel. It should be noted that the shearing edges 26 and 27 are continuous along the full width of the sole section.

Similar shearing edges 28 and 29 are provided adjacent to the upper and lower faces of the front sole section 13, said edges extending transversely of the section from one side thereof to the other. Between the hinge barrels 30 and 31, each of which extends inwardly for a distance from the sides of sole section 13, the rear edge portion 32 of the front sole section is grooved in the manner indicated at 21, to accommodate the cylindrical outer surface of the hinge barrel 24 carried by the rear sole section. The hinge barrels 30 and 31 are bored lengthwise, as indicated at 33 and 34 to receive a hinge pin 35. In that form of the invention illustrated by Figs. 1, 2 and 3, the hinge barrels are integral with the front sole section.

When the front and rear sole sections are joined by the hinge pin as indicated in Fig. 2, each hinge barrel is accommodated by an opposed channel. The drawings illustrate a structure embodying a minimum number of hinge barrels that operate in a satisfactory manner to hinge the parts together, however, it should readily be understood that the number of hinge barrels may be increased if desired. Referring now to Figs. 3 and 4, which shows the hinge structure of the front and rear sections in detail, it should be observed that the edge 26 that bounds the channel 21 at the upper surface of the sole section, is shaped in the manner of a chisel, with the beveled surface 36 inclined downwardly and outwardly of the upper surface 14. Similarly, the tapered surface 37 of the edge 28 is inclined downwardly and outwardly of the upper surface of sole section 13. These co-operative tapered areas normally assume the position indicated by Fig. 2, wherein they are spaced apart when the space at 38 is at its minimum, that is, when the sole sections are in a normally substantially aligned condition. Upon moving the front section 13 upwardly about its pivot 35, the chisel edges 26 and 28 will approach each other along the full length of the sections, to the limit established by the normal distance between them. The space 38 thereupon will be widened, leaving the chisel edges 27 and 29 (Fig. 4) separated. When therefore the front sole section 13 is moved downwardly to the Fig. 2 position, the chisel edges 27 and 29 will close upon each other, and their tapered surfaces 38 and 39 will act as wedges for ejecting from the joint any dirt or other material which might be compacted at the groove 38 (Fig. 2) in the absence of such wedging and ejecting means. It will accordingly be understood that the hinge joint may properly be considered a self-cleaning joint. Thus the relatively sharp edges 27 and 29 scrape the foreign matter from the hinge barrels upon which they rest, while the tapered surfaces 38 and 39 cooperate as wedges to eject the foreign matter bodily from the joint, rather than permit it to become compacted therein. The same character of action takes place between the non-compacting shearing edges 26 and 28 near the upper surfaces of the front and rear sole sections, so that this area or portion of the hinge means is likewise rendered self-cleaning. It may here

be stated that the reference character 40 in each of Figs. 2 and 4, indicates the part-cylindrical groove between the hinge barrels 30 and 31, this groove being adapted to nicely accommodate the cylindrical outer surface of the hinge barrel 24 of sole section 12.

As is evident from an examination of Figs. 2, 3 and 4, the scraping edge 26 is somewhat less than 180° distant from the scraping edge 27, and the 10 scraping edge 28 is less than 180° distant from the edge 29, in order that the sole sections may hinge relative to one another. In Fig. 2, the edges 27 and 29 are in substantial line abutment, thereby limiting the clockwise movement of front section 13 relative to rear section 12. This leaves the upper shearing edges separated, the distance between them determining the extent to which the section 13 may be rotated in counterclockwise direction relative to section 12. From the foregoing explanation, it should readily be appreciated why the upper and lower chisel edges of a section should not be disposed at opposite ends of a diameter of the adjacent hinge barrel, if the front and rear sections are to have hinging movement. Upon each hinging movement, the co-operative beveled chisel portions on the sections will scrape the hinge barrels, and will pinch off and eject any foreign matter outwardly of the hinge joint, without any tendency to compact such foreign matter into the joint. As stated previously herein, the hinge pin should be located midway between the chisel edges of the sections.

In the modified form of the invention illustrated by Fig. 5, the rear sole section 112 is grooved as 35 at 121 uninterruptedly across the sole section, and the remaining edges are beveled as at 136 and 138 to provide the sharp scraping edges 126 and 127 corresponding to the illustration and explanation of Fig. 3. Fig. 5 distinguishes from Fig. 4 in that the hinge barrel 124 is made separate from the rear sole section, rather than integral therewith, and is secured within the middle region of the groove with the use of suitable fastening devices, such as nails or brads 44, either with or 45 without the aid of an adhesive applied to the groove 121 where the hinge barrel 124 is to seat. The separate hinge barrel 124 is to assume the same relationship to the groove and to the bounding chisel edges, as is illustrated by Fig. 1. In resorting to this type of construction, the front sole section may be similarly equipped with separate hinge barrels, in the same manner as is suggested by Fig. 5.

In the second modification of Fig. 6, which corresponds with Fig. 4 in that it represents the front sole section, the front sole section 113 has its hinge barrels 130 of approximately the same diameter as the thickness of the sole section, so that the scraping edges indicated at 128 and 129 are quite sharp and thin and are without the bevels such as are indicated at 37 and 39 of Fig. 4. The dotted line 140 indicates the groove between the spaced hinge barrels, which are to be related as in Fig. 1, at 30 and 31. As 65 will be understood, the rear sole section as well as the front sole section 113 of Fig. 6, would be correspondingly grooved and barreled in the manner suggested by Fig. 1, to present a hinge connection with scraping edges for dislodging foreign matter tending to enter the hinge joint.

The step indicated at 42 of Figs. 1, 2 and 3 may be incorporated in the structure, if desired, to reinforce the structure at the hinge, adding to its durability by assuming the weight of the wearer's body while the front sole section is in

contact with a walking surface, thereby relieving the hinge structure of such weight and the strain accompanying same. The character 43 indicates a pad in the nature of an insole, that may cover the entire upper surface of both sole sections in the finished condition of the article, it being understood that such pad or sheet 43 will be flexible so as not to interfere with the hinging movements of the front and rear sections.

The hinge pin may be of a single piece, or of two pieces each inserted inwardly from the outer sides of the hinge barrels, and by preference said hinge pin is made slightly shorter than the width of the front sole section at the hinge barrels 30 and 31, so that the ends of the hinge pin might be puttied in at the outer ends of the bores to preclude accidental displacement of the hinge pin. As stated previously herein the form of the holding means 18 and 19 which perform to keep the article against the wearer's foot is a matter wholly immaterial to the present invention. In some forms of the device, the strap 18 might be replaced by a counter, if desired.

Various other modifications and changes may be made in the structural details of the device, within the scope of the appended claims, without departing from the spirit of the invention.

What is claimed is:

1. An article of footwear which comprises in combination, a substantially inflexible rear section including a heel support, and a substantially inflexible front section to support the forward end of the human foot, each of said sections having upper and lower surfaces each terminating in a straight transverse hinge edge extending continuously across the front and rear sections, and hinge means joining said sections at said edges, said hinge means including a plurality of interfitting hinge barrels and a connecting hinge pin extending through the barrels in substantial parallelism with said hinge edges, with the axis of the pin equally distant from the upper and lower surfaces of the front and rear sections.

2. An article of footwear which comprises in combination, a substantially inflexible rear section including a heel support, and a substantially inflexible front section to support the forward end of the human foot, each of said sections having upper and lower surfaces each terminating in a straight transverse hinge edge extending continuously across the front and rear sections, and hinge means joining said sections at said edges, said hinge means including a plurality of interfitting hinge barrels and a connecting hinge pin extending through the barrels in substantial parallelism with said hinge edges, and means operative to clear the hinge means of foreign matter upon relative hinging movement of the front and rear sections.

3. An article of footwear which comprises in combination, a substantially inflexible rear section including a heel support, and a substantially inflexible front section to support the forward end of the human foot, each of said sections having upper and lower surfaces and a substantially straight transverse hinge edge, and hinge means joining said sections at said edges, said hinge means including a plurality of interfitting hinge barrels and a connecting hinge pin extending through the barrels in substantial parallelism with said hinge edges, and a pair of straight shearing edges extending continuously across each of said sections at their

upper and lower surfaces and arranged to cooperate during hinging movements of the sections, to dislodge foreign matter at the hinge means and prevent compacting of such foreign matter between the sections.

4. An article of footwear which comprises in combination, a substantially inflexible rear section including a heel support, and a substantially inflexible front section to support the forward end of the human foot, each of said sections having upper and lower surfaces and a substantially straight transverse hinge edge, and hinge means joining said sections at said edges, said hinge means including a plurality of interfitting hinge barrels and a connecting hinge pin extending through the barrels in substantial parallelism with said hinge edges, and cooperative beveled chisel edges on the sections located to scrape the hinge barrels and to squeeze foreign matter outwardly of the joint provided by the hinge without compacting the foreign matter into the joint.

5. An article of footwear which comprises in combination, a substantially inflexible rear section including a heel support and a forward edge, and a substantially inflexible front section having a rear edge, said edges of the sections each being grooved longitudinally and continuously from one side of a section to the other side thereof, and bored cylindrical hinge barrels fixed in the grooves in staggered relationship, with the bores of the hinge barrels disposed in alignment for reception of a hinge pin when the barrels of the sections are interfitted to provide a hinge, a hinge barrel of one section being projected between the hinge barrels of the other section and into the groove of said other section, said groove being complementarily curved to fit the cylindrical form of the hinge barrel of said one section.

6. An article of footwear which comprises in combination, a substantially inflexible rear section including a heel support and a forward edge, and a substantially inflexible front section having a rear edge, said edges of the sections each being grooved longitudinally and continuously from one side of a section to the other side thereof, and bored cylindrical hinge barrels fixed in the grooves in staggered relationship, with the bores of the hinge barrels disposed in alignment for reception of a hinge pin when the barrels of the sections are interfitted to provide a hinge, the hinge barrels of one section being projected into the groove of the other section, said groove being complementarily curved to fit the cylindrical form of the hinge barrels of said one section, and shearing edges on the sections defining the grooves, said shearing edges being tapered to scrape an opposing hinge barrel and to cooperate with a similarly tapered shearing edge on the opposite section to squeeze out and dislodge from the hinge assembly any foreign matter tending to compact therein.

7. An article of footwear which comprises in combination, a substantially inflexible rear section including a heel support and a forward edge, and a substantially inflexible front section having a rear edge, said edges of the sections being straight and coextensive with the width of each section, one of said sections being grooved along its edge and flanked by a pair of bored aligned hinge barrels integral with said one section, the radii of the grooves and aligned barrels having a common center line parallel to the section edge, the other section including a bored integral hinge barrel flanked at its ends by grooves receptive of

the hinge barrels of said one section while the hinge barrel of said other section seats within the groove of said one section, and hinge pin means extended through the barrel bores to complete the hinge assembly.

8. An article of footwear which comprises, in combination, a substantially inflexible rear section including a heel support and a forward edge, and a substantially inflexible front section having a rear edge, said edges of the sections being coextensive with the width of each section, one of said sections being grooved along its edge and flanked by a pair of bored aligned hinge barrels integral with said one section, the radii of the grooves and aligned barrels having a com-

15

mon center line parallel to the section edge, the other section including a bored integral hinge barrel flanked at its ends by grooves receptive of the hinge barrels of said one section while the hinge barrel of said other section seats within the groove of said one section, and hinge pin means extended through the barrel bores to complete the hinge assembly, said section edges in the region of the hinge barrels and grooves being relatively sharp and arranged to meet with a pinching action to bodily eject foreign matter from the hinge joint as the sections move relatively about the hinge pin means.
